THERMOSTATIC CONTROL

Fritz Henry Mumberg, Philadelphia, Pa.

Application December 21, 1950, Serial No. 202,073

4 Claims. (Cl. 200—141)

1

This invention relates to a thermal regulation device and more particularly to a thermal control in which mercury is the thermal sensitive substance and an adjustable contact is provided for making electrical contact with the mercury.

It is an object of this invention to provide a thermal sensitive device employing a column of mercury which can be easily increased and decreased in volume.

It is another object of this invention to provide a thermal sensitive device having an adjustable electrical contact completed between a mercury column and an adjustable wire contact both of which are sealed in a tube.

It is a still further object of this invention to provide a thermal sensitive device in which an adjustable contact sealed in a tube completes an electrical circuit by contacting a mercury column and which is electrically attached to a wire outside of the sealed tube by means which do not hinder the adjustment of said adjustable contact.

These and other objects of this invention will become more apparent upon consideration of the following description taken together with the accompanying drawings in which:

Fig. 1 is a front sectional view of the thermal control of this invention;

Fig. 2 is a front sectional view of the upper end of the thermal control of Fig. 1;

Fig. 3 is an enlarged sectional view of a portion of the thermal control of Fig. 1;

Fig. 4 is a radial section of the thermal control of this invention taken on lines 4—4 of Fig. 2 in the direction of the arrows;

Fig. 5 is a front sectional view of another thermal control of this invention;

Fig. 6 is a front sectional view of a central section of the thermal control shown in Fig. 5;

Fig. 7 is a radial section of the thermal control of Fig. 6 taken on line 7—7 in the direction of the arrows; and

Fig. 8 is a radial section of the thermal control of Fig. 6 taken on line 8—8 in the direction of the arrows.

This application is a continuation in part of my copending application, Serial No. 142,207, filed February 3, 1950, now abandoned, for Thermostatic Control.

A thermal control 10 is shown in Fig. 1 made up of an outer tube 11 enveloping an inner tube 12 molded into its lower end into a thickened stem 13. At the bottom of the thickened stem 13 a bulb-like mercury reservoir 14 is provided from which a capillary tube 15 extends upward through the thick walls of the stem 13 to thin walls 16 at the lower end of the outer envelope tube 11. A

2

short distance up the envelope tube 11, the thin walls 16 widen to form the inner tube 12 which extends upward through the outer tube 11 to a pointed seal-off 17 adjacent the upper end of the thermal control 10.

The inner tube 12 is divided into two compartments A and B by a central radial wall 18. The compartment A is the lower compartment as shown in Fig. 1 and contains walls 19 which are extensions of the walls 16 above the point where the lower end of the tube 12 branches off from the walls 16. The walls 19 extend upwardly forming the upper end of the capillary tube to a point where, spreading out, a cup 20 is formed. The cup 20 has a flared-out upper lip 21 which abuts the inner surface of the compartment A throughout its circumference. The upper compartment B contains a sleeve 22 as shown best in Fig. 2. The sleeve 22 is supported at the upper end of compartment B. Referring to Fig. 4, it is seen that the sleeve 22 is centered in the compartment B of the tube 12 by an insulating separator 23 which is corrugated to space the sleeve 22 from the inner surface of the compartment B and to hold it in position by a friction fit. Supported in turn in the sleeve 22 is a metal threaded rod 24 as shown in Figs. 1 and 2. The lower edge of the sleeve 22 is turned inward to form a seat which grasps and supports a metal block 25. The block 25 is centrally threaded to receive and support the threaded rod 24 which is thus centered and supported in the compartment B of the inner tube 12. At its lower end, the rod 24 is provided with a slit which receives and holds a wire 26. The wire 26 extends downwardly from the threaded rod 24 and through a suitable aperture in the central wall 18 into the lower compartment A. In the lower compartment A, the wire 26 extends into the cup 20 and into the upper end of the capillary tube 15.

A thermal control 110 is shown in Fig. 5 made up of an outer tube 111 and an inner tube 112. At the lower end of the outer tube 111 there is a thickened stem 113 which has at its end a mercury reservoir 114. A capillary tube 115 extends axially upward through the thick walls of the stem 113 from the reservoir 114. At the upper end of the thickened stem 113 a thin wall 116 extends to the lower end of the inner tube 112. The capillary tube 115 extends upward axially through the tubular wall 116. The thin wall 116 widens to form the inner tube 112 which, in turn, extends upward through the outer tube 111 to a point at seal-off 117 adjacent the upper end of the thermal control 110.

The inner tube 112 is divided into two com-

partments U and L by a narrow waist portion 118. The compartment L is the lower compartment shown in Fig. 5 and contains a wall 119 which is a straight extension of the wall 116 above and within the lower end of the inner tube 112. The wall 119 extends upwardly and at its upper end spreads out into a cup 120. The capillary tube 115 extends axially within the wall 119 to the cup 120. The cup 120 has a lip 121 which peripherally contacts the inner wall of the tube 112 throughout its entire circumference. The waist 118 contains a bolt 122 which has an external thread 123 and receives a threaded rod 124 in an internal thread 125 bored axially through its center. The threaded rod 124 carries a contact wire 126 which extends downwardly from the threaded rod 124 through the lower compartment L and into the cup 120 and the upper end of the capillary tube 115. As shown in Fig. 6, the bolt 122 is held in place on the waist 118 by a head 145 formed on the lower end of the bolt 122 and a nut 146 screwing on the threads 123. The head 145 has a sloping wall 147 and the nut 146 bears against a spring 148. The waist 118 forms a circular shoulder 149 at the bottom of the upper compartment U and a circular shoulder 150 at the top of the lower compartment L. The spring 148 seats on the shoulder 149 and is urged thereagainst by the nut 146. The sloping wall 147 seats against the shoulder 150 and is drawn thereagainst by the tightening action of the nut 146 on the threads 123. The spring 148 pressed between the shoulder 149 and the nut 146 applies a seating force on the wall 147 against the bolt 150. This seating force between the smooth wall 147 and the smooth shoulder 150 can provide a mercury tight fit between these parts. A body of mercury 151 is contained in the lower part of the upper compartment view around the bolt 122 and the spring 148 and nut 146.

The adjustment of the thermal control is obtained by magnetism between the parts at the upper end of the thermal control. As seen in Fig. 2, the upper end of the outer tube 11 is covered by a cap 27 which fits snugly over the top and down the outer surface of the walls of the tubes 11 for a short distance. An annular field magnet 28 encircles the tube 11 immediately below the cap 27 and is supported on the cap 27 by a thread coupling 29. The field magnet 28 creates a directional magnetic field having lines of force aligned radially across the tubes 11 and 12 in the area encompassed by the magnet 28. The threaded rod 124 is so positioned in the compartment B that its upper end lies within this magnetic field. An armature 30 is formed on the upper end of the threaded rod 124. The armature 30 is formed of a magnetic responsive substance and shaped as to be under the influence of the magnetic field of the field magnet 28. The rod 124 is so threaded in the block 25 as to be readily rotatable in the block 25. The coupling 29 is provided with an inwardly turned rim 31 which engages outwardly turned flange 32 on the lower end of the cap 27. The fit provided between the rim 31 and the flange 32 is sufficiently loose to permit rotation of the coupling 29 on the cap 27. Consequently, the field magnet 28 can be rotated around the outer tube 11 and the direction of the lines of force of its consequent magnetic field within the tubes 11 and 12 can be correspondingly shifted. When the lines of force are thus revolved, the armature 30 is correspondingly influenced and is rotated on the axis of the

threaded rod. The threaded rod being screwed into the block 25 will thread up or down through the block 25 depending upon the direction of the rotation of the armature 30 as brought about by the rotation of the field magnet 28 as seen as looking downward from above in Fig. 4. When the armature 30 is rotated clockwise, the threaded rod 124 screws downwardly through the block 25 while conversely, when the armature 30 is rotated counter-clockwise, the threaded rod 124 screws upwardly through the stationary block 25. Thus, in this manner, the rotation of the field magnet 28 can be employed to alter and determine the axial position of the threaded rod 124, and consequently, the wire 126.

Similarly, the wire 126 can be moved up and down in the lower compartment L of the thermal control 110 shown in Figs. 5 and 6. An armature 130 is provided at the upper end of threaded rod 124. This armature 130 may be subjected to the action of a field magnet and rotated in the same manner as the armature 30 referred to above in connection with Figs. 1, 2 and 4. The field magnet and cap structure is not shown in Figs. 5 and 6 but the cap 27, field magnet 28 and coupling 29 of Figs. 1, 2 and 4 can be applied to the thermal control of Figs. 5 and 6 and rotate the armature 130 with equal facility. Such a rotation of the armature 130 causes the threaded rod 124 to rotate in the threaded bore. When the threaded rod 124 rotates in a counter-clockwise direction as seen in Fig. 7, the armature 130, threaded rod 124 and wire 126 assembly moves upward in the thermal control 110. Conversely, when the threaded rod rotates clockwise as seen in Fig. 7, the assembly moves downward in the control 110.

The electrical contact in the thermal control 110 is achieved by making and breaking contact between two wires 133 and 134 which enter the thermal control 110 at the top. The wire 134 extends into the outer tube 111 and downwardly between the outer tube 111 and the inner tube 112 on the right side, as seen in the figures to a knob 136 formed on the thin wall 116 adjacent the lower end of the tube 111. The wire 134 is anchored on the knob 136 as shown in Fig. 6. A short lead-in wire 137 is wrapped around the wire immediately above the knob 136 and passing through the knob 136 is bent at right angles to penetrate the wall 116 and extend into the capillary tube 115 and thus provide an electrical contact surface 138 in the capillary tube at this point. The other wire 133 extends down the left side of the tube 112 a short distance to a girdle 139 of solder encircling the waist 118. As shown in Fig. 8, the solder girdle 139 anchors the end of the wire 133. A lead-in wire 141 extends from the solder girdle 139 through the inner tube 112 and projects into and contacts the mercury pool 151 in the upper compartment U.

The mercury pool 151 surrounds and is in contact with the metallic bolt 122. The threaded rod 124 in turn is in electrical contact with the bolt 122. Thus, the wire 126 is in electrical contact with the lead-in wire 133 through the solder girdle 139, the lead-in wire 141, the mercury pool 151, the bolt 122 and the threaded rod 124.

As in the thermal control of Figs. 1 to 4, mercury fills the reservoir 114 and capillary tube 115. The level of the mercury in the capillary tube 115 can be adjusted while the thermal control 110 is not in operation by heating the reservoir 114 to expand the column of mercury in the tube 115 up into the cup 120 where it will reach the level of a port 144 in one side of the

cup 120. The mercury upon increased heat applied to the reservoir 114 will run out the port 144 and collect in the bottom of the compartment L. The mercury thus overflowing can be stored in the compartment L. When the reservoir 114 is subsequently cooled, the level of the mercury in column 115 will recede from the cup 120 to any predetermined point according to the temperature at which the thermal control is to be operated.

The operation of the two thermal control devices in the above embodiments of this invention is essentially the same. The following description of the operation of the invention is therefore hereinafter described in connection with the embodiment shown in Figs. 5 to 8. It will be understood however that the operation of the embodiment shown in Figs. 1 to 4 is essentially the same. In operation, this device is first adjusted to a desired range of temperatures by predetermining the level of the mercury column in the capillary tube 115 by the above described procedure. A second adjustment is obtained by the axial movement of the rod 124 as described in connection with the field magnet. With these two adjustments, the thermal control 110 can be set to open and close the contact between the wires 133 and 134 over a wide range of temperatures. The contact between the wires 133 and 134 is closed by the column of mercury first contacting contact 138 and then rising to contact wire 126.

The thermal control of this invention is susceptible of adjustment to sensitivity in heat changes over a wide variety of temperatures. At the same time, the control 110 is adjustable to be accurately actuated at a predetermined temperature by a change in temperature. The sensitivity of this thermal control is based upon the contact which is made or broken between the wires 133 and 134 by the wire 126 and the mercury column in the capillary tube 115. The contact is established from wire 133 to wire 134 through the girdle element 139, the lead in wire 141, the mercury pool 151, the threaded bolt 122, the threaded rod 124, the wire 126, the mercury in the capillary tube 115, the contact 138 on the lead-in wire 137 which contacts the wire 134. Thus, the circuit between the wires 133 and 134 that is completed by the thermal control 110 is dependent upon contact between the wire 126 and the column of mercury in the capillary tube 115. It will be seen that the place of this contact can be varied and that by thus varying the point of contact it is possible to vary the temperature at which the electrical circuit is completed. This variation of the temperature at which the circuit will be completed is dependent upon both the amount of extension of the wire 126 into the capillary tube 115 and the height of the mercury column in the capillary tube 115 at any given temperature. Also, this variability provides the thermal control 110 of this invention with a wide range of temperatures at which it will operate and with a high selective sensitivity in operating at any temperature in this wide range of temperatures.

The higher the column of mercury stands in the capillary tube 115 the lower the temperature at which the circuit will be completed for any given position of the wire 126. Correspondingly, the further the wire 126 is inserted in the capillary tube 115 the lower the temperature at which the circuit will be completed for any given amount of mercury in the capillary tube 115. The tem-

perature for closing the circuit can thus be varied by increasing or decreasing the amount of mercury in the capillary tube and thereby lower or raise the level of the mercury column at any given temperature. The temperature of the completion of the circuit may also be varied by the axial movement of the wire 126 in or out of the capillary tube 115. The wire 126 may be readily moved axially by rotation of the field magnet as described above. By rotating the field magnet, the armature 130 is rotated either in a clockwise or a counter-clockwise motion as seen in Figs. 7 and 8 and the threaded rod 124 is either moved down or up axially. The effect of this rotation and axial movement of the rod is to move the wire 126 correspondingly in and out of the capillary tube 115.

At the same time, the level of the mercury column in the capillary tube for any given temperature may be lowered by expelling excess mercury from the capillary tube through port 144 in cup 120. The level of the mercury column may be raised by adding mercury from the supply of excess mercury lying in the bottom of compartment L. In the operation of this invention, the level of the mercury column is lowered by heating the mercury in the reservoir to drive the top of the column up into the cup 120 to a point where an excess of the mercury will escape through port 144 into the compartment L. When the control is held in a vertical position, this excess supply of mercury will recede in the capillary tube 115 to a point which is dependent upon the amount of mercury expressed from the cup 120 which, in turn, is dependent upon the temperature to which the mercury is raised. The level of the mercury, in the capillary tube 115, in turn, can be raised by heating the reservoir 114 and the column of mercury to drive the level of the column of mercury into the cup 120 to a point above the bottom of the cup where the walls widen out. The control 110 may then be held in a horizontal position with the port 144 facing downward and the excess supply of mercury flowing up around the base of the cup 120 will enter the port 144. Upon turning regulating device 116 through a semi-circle, a substantial amount of the excess mercury will be trapped in the cup 120 and come in contact and merge with the top of the column of mercury in the tube 115. The amount of mercury available for the column in tube 115 will thus be increased. Upon decreasing the temperature of the mercury column this trapped mercury will move into the column and thus raise the level of the mercury column in tube 115. The column of mercury may be further increased by additional mercury from the excess supply incorporated into the column by a repetition of the above described procedure at progressively lower temperatures. Thus, it is possible both to increase and decrease the amount of mercury in the capillary tube and to raise and lower the level of the mercury column.

With the two adjustments of the point of circuit closing thus obtainable, it is possible to establish a predetermined temperature for closing the electrical circuit from a wide variety of temperature changes. Furthermore, because of the accuracy of the thermal control of this invention and the minute adjustments in relative position between the thermal electrical contacts, it is possible to predetermine the temperature point of electrical contact to within a small fraction of a degree of temperature. Another ad-

vantage of this invention is found in the electrical contact that is made with the rotating screw threaded rods 24 or 124. These rods are in continuous electrical contact with the wires 33 or 133 respectively without interference of their ability to rotate in the block 25 or bolt 122, respectively and adjust the position of the wires 26 or 126 respectively. As a result of this advantage, it is possible to adjust the position of the wires 26 or 126 by rotation of the screw threaded rods 24 or 124 without disturbance of the electrical contact between the wires 33 or 133 and 26 or 126 respectively.

Among other advantages, this invention provides a mercury controlled device in which the amount of mercury in the contacting column can be easily varied. Another advantage of this invention is the continuous electrical contact made with a longitudinally adjustable contact element without hindering the adjustment of the contact element. The mercury in the capillary column of this invention is raised and lowered by adding to or taking from the reservoir in the lower compartment. It is an advantage of this invention that in adding mercury to the column in the capillary tube that the cup lip is in contact with the inner wall of the compartment throughout its periphery. This contact is made possible by the use of the escape port in the side of the cup. The contact between the lip and the wall is advantageous in providing a large area which can receive the mercury from the reservoir through the escape port.

Another advantage of this invention is seen in the form shown in Figs. 5, 6, 7 and 8. This advantage is the forming of the inner tube as one continuous envelope, subdivided merely by a waist portion at which the inner tube walls converge toward each other but do not contact. The seal that is obtained at this waist portion is also advantageous in its simplicity of manufacture. The waist portion with its bolt head seal is a strong structure. The electrical contact obtained by the pool of mercury contained in the upper compartment above the waist supplies a highly conductive contact between the conducting wire and the threaded rod with the greatest mobility as the mercury which completes the contact is fluid.

It will be apparent to those skilled in the art that various modifications can be made upon the embodiment of the invention shown and described herein without parting from the principles of the invention as set forth and for that reason it is not intended that it should be limited other than by the scope of the appended claims.

I claim:

1. A thermal control for closing an electrical circuit comprising a tube, a separating section of said tube, an upper compartment in said tube above said separating section, a lower compartment in said tube below said separating section, a central passage through said separating section, a shoulder on the inner surface of said tube wall at each end of said passage, a member extending axially through said passage, a head on one end of said member bearing against one of said shoulders to provide a mercury tight fit, a first body of mercury in said lower compartment forming one of said separate bodies of mercury, a second body of mercury in said upper compartment forming

the other of said separate bodies of mercury and positioned adjacent to said passage and separate from said lower compartment by said mercury tight fit, a lead-in wire electrically contacting said second mercury body and an axially moving contact wire extending through said member from said upper compartment to said lower compartment to connect electrically said lead-in wire to said first body of mercury through said second body of mercury.

2. In a tube having an electrical contact as claimed in claim 1, a spring bearing against the other of said shoulders on the inner surface of said tube, said spring encircling said member and a nut threaded on said member bearing against said spring and said other shoulder.

3. A thermal control for closing an electrical circuit comprising a tube, a separating section of said tube, a first compartment in said tube on one side of said separating section, a second compartment in said tube at the other side of said separating section, a central passage through said separating section, a surface at an angle to the axis of the tube at each end of said central passage, a member extending axially through said passage, a portion of said member abutting against the inner surface of said tube to provide a mercury tight fit of said member in said tube, a first body of mercury in the first compartment of said tube, a second body of mercury in the second compartment of said tube and separated from said first compartment and said first pool of mercury by said mercury-tight fit, a lead-in wire passing through the tube wall electrically contacting said second mercury body and an axially moving contact wire extending through said member from said second compartment to said first compartment to connect electrically said lead-in wire to said first body of mercury through said second body of mercury.

4. A thermal control for closing an electrical circuit comprising a tube, a separating section in said tube, an upper compartment in said tube above said separating section, a lower compartment in said tube below said separating section, a surface at an angle to the axis of the tube at each end of said central passage, a member extending axially through said passage, a portion of said member abutting against the inner surface of said tube to provide a mercury tight fit, a first body of mercury in said lower compartment, a second body of mercury in said upper compartment positioned adjacent to said passage and separate from said lower compartment by said mercury tight fit, a lead-in wire passing through the tube wall electrically contacting said second mercury body, and an axially moving contact wire extending through said member from said upper compartment to said lower compartment to connect electrically said lead-in wire to said first body of mercury through said second body of mercury.
